UNITED STATES PATENT OFFICE

JOHN H. FRANCIS, OF CLEVELAND, OHIO, ASSIGNOR TO KILBY MANUFACTURING COMPANY, OF CLEVELAND, OHIO, A CORPORATION OF OHIO

ROTOR CONSTRUCTION FOR GAS CLEANERS

Application filed October 23, 1929. Serial No. 401,742.

My invention relates to a rotor construction for mechanical gas cleaners, and has particular reference to an improvement in a washer commonly known as the Thiesen type of gas cleaner and disintegrator.

The primary object of my invention is the provision of a beater or blade construction which is removably secured to the rotary element in the gas cleaner which disintegrates the gas and brings the cleansing medium and the gas into close relationship with each other whereby the particles of dirt are removed from the gas passage, and which, when broken, can be easily and quickly replaced without replacing the rotor plates.

In securing these blades or cleaning members in position in the rotary element, it has been the practice heretofore to cast the cage and rotary element in one piece so that if it became necessary to remove the blades the entire structure had to be replaced. In common practice the rings in which these blades were mounted were cast around the blades which had been placed in stable position in the mold so that the molten metal in cooling held the blades firmly in position. If one of these blades became broken or mutilated in such manner that it would not perform its function, an entire new member would have to be supplied. In my improved structure, if a blade becomes damaged or mutilated in such manner that it will not properly function, this particular blade can be removed from the washer and a new one inserted without tearing down the washer structure or providing an entirely new structure.

These and other objects will be more fully and better understood by reference to the sheet of drawings, in which—

Figure 1 is an elevational view partially in section of a gas washer;

Figure 2 is a sectional view partially in elevation illustrating the beater rings of the gas cleaner;

Figure 3 is a cross sectional view on line 3—3 of Figure 2;

Figure 4 is an elevational view of one of the ends of the blades;

Figure 5 is an end elevational view of the blades illustrated in Figure 4;

Figure 6 is a view of one of the blades after the trunnion has been formed thereon; and

Figure 7 is an end elevational view of the blade shown in Figure 6.

Referring now specifically to the drawings, and in which like reference characters refer to like parts throughout, a casing 10 is shown having a gas inlet (not shown) at one side thereof, and having a gas outlet 11 therefrom with a shaft 12 mounted therein in bearings 13, 13, which is driven by a motor or other suitable means. The shaft 12 extends through the casing 10 and has a circular plate member 14 mounted thereon at the central portion of the casing, with paddles 15, 15 mounted thereon adapted to beat the gas and force it through the container, and also has a cylindrical member 16 mounted thereon having openings in the walls thereof through which water, which is conducted into the casing through water supply pipes 17 and 18 respectively, is mixed with the gas passing through the casing. Water outlet pipes 19, 19 are provided at the bottom of the casing through which water flows carrying with it the dirt particles which are removed from the gas.

Attached to the plate member 14 and extending outward therefrom in each direction is a plurality of blades 20, 20 which, together with other blades extending in an inward direction from the outer side of the casing, forms a beating arrangement which in effect is a cage formation, and it is with these blades 20, 20 that my invention has particularly to do.

A pair of plates 21 and 22 are provided which are circular in form and which are secured to the member 14 by means of a plurality of bolts 23, 23. Holes 24, 24 are formed in the plates 21 and 22 respectively, within which the blades 20 are mounted. The blades 20, 20 are formed in sets in the embodiment shown, four sets of blades being provided on each side of the plate 14, the blades being in radial spaced relation with each other and are also spaced around the plates 21 and 22.

Rings 25, 25 are provided which are secured to the outer ends of the blades 20 and serve to stiffen and hold these blades in proper alignment so they will not engage the stationary blades, sets of which are placed between the sets of rotatable blades 20, 20.

A pair of circular plates 26 and 27 are provided which are secured to the outer wall of the casing and which have a plurality of bars 28, 28 mounted therein which extend inwardly and terminate adjacent the plates 21 and 22, with a plurality of rings 29, 29 being secured to the inner ends of the members 28 so that they are also held in proper spaced alignment with respect to the rotatable blades 20, 20.

In making the plates 21 and blades 20 it has been the common practice heretofore to cast the plates 21 with the blades being inserted in position in the mold in which the plates are cast and the molten metal poured into the mold, so that when the metal hardens the blades 20, 20 are in position in the plates 21 and 22. This practice has been objectionable because if the blades become broken or distorted it has been impossible to remove them from the plates 21 and 22, and an entire new unit has had to be built and the old unit discarded.

In Figures 4 to 7 inclusive is illustrated a form of the blade 20 which I employ in my improved construction and which comprises a reinforcing member 30 which is rectangular in cross section, and to which the blades 20 are spot-welded a plurality of times as at 31, 31. The blades 20 are preferably of angular formation while the reinforcing member 30 is rectangular in cross section and is of sufficient size so that it engages in the inside angle of the member 20, which, being spot-welded against said member, forms the reinforcing member and the blade firmly together at the end of the blades. The blade in the reinforcing member is thereupon turned in a lathe or other suitable device until a round trunnion 32 is formed thereon at one of the ends, with a shoulder 33 being provided adjacent the trunnion portion 32 with a cupped end 34 being provided. The openings 24, 24 which are formed in the circular plates 21 and 22 are of substantially the same contour as the trunnions 32, formed on the ends of the blades and formed of a sufficient size so that the blades are driven into the holes 24 in the plates 21 and 22 and the cupped ends 34 peened over with a hammer, thereby fixing the blades firmly in position in the plates 21 and 22. The holes 24 are slightly countersunk at one side so that a smooth inner face is formed on the plates 21 and 22 so that they engage firmly against the side of the member 14.

With this form of device it will be readily understood that if one of the blades 20 becomes broken or distorted in service it is only

necessary to remove the plates 21 and 22 from the casing, the broken blade removed, and a new blade inserted in place by the operation hereinabove described.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:

1. Rotor construction for gas cleaners, comprising in combination a rotatable shaft, a member mounted thereon, plates detachably secured to said member, and blades mounted upon said plates, the said plates having openings formed therein and said blades having reinforcing members secured thereto and shaped to conform to the openings in said plates, the said blades having their ends upset whereby they are held in said plates.

2. Rotor construction for gas cleaners, comprising in combination a rotatable shaft, a member mounted thereon, plates detachably secured to said member, and blades mounted upon said plates, the said plates having holes formed therein and the said blades being angular in shape and having a reinforcing block secured thereto, the reinforcing block and said blades being shaped to conform to the holes in said plate, the end of the blades being upset whereby the said blades are held in said plates.

3. A blade for a gas cleaner, comprising an angular member and a reinforcing block secured thereto, the reinforcing member and the end of said blade being shaped to conform to an opening formed in a mounting member for said blade, the said reinforcing member having an abutting shoulder formed thereon and being adapted to be upset to be held in position in a mounting plate.

Signed at Cleveland, Ohio, this 18th day of October, 1929.

JOHN H. FRANCIS.
